UNITED STATES PATENT OFFICE.

JOHN H. PILLINGS, OF HAMILTON, OHIO.

COMBINATION-LOCK.

1,355,776.

Specification of Letters Patent.

Patented Oct. 12, 1920.

Application filed November 18, 1919. Serial No. 338,827.

To all whom it may concern:

Be it known that I, JOHN H. PILLINGS, a citizen of the United States, residing at Hamilton, in the county of Butler and State 5 of Ohio, have invented certain new and useful Improvements in Combination-Locks; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in combination locks for switch box keys for automobiles, and consists of a simple and efficient device of this nature adapted to be applied to the switch box and 20 affording a secure means for holding the switch key of the type commonly used upon Ford cars.

The invention consists of a simple and efficient apparatus of this nature having 25 various details of construction, combination and arrangement of parts which will be hereinafter fully described, shown in the accompanying drawings and then specifically defined in the appended claims.

30 I illustrate my invention in the accompanying drawings which, with the numerals of reference marked thereon, form a part of this application, and in which:

Figure 1 is a side elevation of the invention shown as applied to a switch box.

Fig. 2 is a front elevation of the device shown in Fig. 1, with the button 12 depressed.

Fig. 3 is a view in elevation with the lid 40 of the casing removed, the button 12 being shown elevated.

Fig. 4 is a view of the inner face of the lid.

Fig. 5 is a cross sectional view on line 4—4 45 of Fig. 2.

Fig. 6 is a sectional view on line 5—5 of Fig. 2.

Figs. 7, 8 and 9 are detail views of the inner faces of the dial plates.

50 Figs. 10, 11 and 12 are detail sectional views transversely through parts of the device.

Fig. 13 is a fragmentary sectional detail view on the line 13—13 of Fig. 3, the key 55 being omitted.

Reference now being had to the details of the drawings by numerals:

1 designates the usual switch box and 2 the key for switching on or off the current, and to the switch box is fastened a casing 3 which may be of any suitable size or shape, and which in the present instance is shown as having a recess 5 extending centrally through the rear wall thereof. A suitable lid 3* forms a closure to the casing and is 60 recessed as at 3*. A yoke 7 has its lower end positioned to have a vertical movement within said recess 5 and the recess 3*, and a post or pin, designated by numeral 9, is fastened to the upper end of the yoke and 65 extends through an aperture 10 in the wall of the casing 3, and upon the outer end of said post or pin is a knob 12. A coiled spring 13 is mounted upon the pin and interposed between the knob and the side wall 70 of the casing, the purpose of said spring being to throw the yoke to its highest position, which will be its unlocked position.

Upon either side of said yoke are the wings 14 which, when the lid is fastened to 80 the casing by screws 15 or other suitable means, is adapted, when the yoke is in a locked position, to engage behind the projections 16 which are mounted upon the inner surface of the lid, thus serving to securely 85 hold the lid in place when the device is in a locked relation with the key of the switch box, even though the screws or other fastening means referred to may have been removed from the lid. Said pin has a contracted end 17 extending into the opening 90 in the yoke and is adapted to engage an aperture in the lug 18 upon the inner face of the lid when the device is in a locked relation, thus affording a further precautionary means for holding the lid upon the casing so that the mechanism within may 95 not be tampered with.

Projecting laterally from the face of the yoke is an integral hook 20 passing through 100 an opening 21 formed in the rear wall of the casing and adapted to engage over the marginal edges of the opening when the yoke is at its farthest downward limit. A pin 21* projects from the side of the lower portion 105 of the yoke which moves in the recess 5 and is adapted to engage a notch 22 formed in the wall of the casing adjacent to said recess 5 and which cooperates with said integral hook upon the upper portion of the yoke to 110

securely hold the latter in place when in a locked position.

The extreme lower end of the yoke is provided with a slot 23, the bottom of which is inclined, and which slot is adapted to receive the upper portion of the key when the yoke is at its lowest limit and which serves as a means for locking the key.

The combination means for locking and 10 unlocking the device consists of the two sleeves, designated respectively by numerals 25 and 26, and a solid member 27, which have respectively the tumblers 25', 26' and 27', and each sleeve has a reduced portion 15 from which project respectively pins 28 and 29 and from said member 27 a pin 30. The tumbler 25' is provided with a notch 31; the tumbler 26' a similar notch 32, and the tumbler 27' a notch 33, the several notches 20 being adapted to be brought into registration with one another and also with the integral tongue 35 upon the yoke to allow the latter to be moved under the influence of said spring 13 to an unlocked position 25 or in such a position that the upper end of the switch key will be free from the slot in the lower portion of the yoke.

Mounted upon the sleeve 25 is a dial 36 having a central opening 37 from which 30 radiate key slots, eight in number being formed therein, and which are adapted to receive the pin projecting from the circumference of the sleeve upon which the dial is mounted, the several key slots being for 35 the purpose of changing the combination. A similar dial 38 is provided with a central opening 39 to fit over the sleeve 26 and is provided with the radial key slots 40 adapted to receive the pin 29, and a third dial 40 disk 41 with a central opening 42 to receive the member 27 and has the radial key slots 43 to receive the pin 30.

The circumference of each dial disk bears letters from A to H and each identifying a 45 transverse line or groove 50.

Assuming the parts are in a locked position as shown in the drawings and it is desired to unlock the same, and assuming that the combination consists of the letters 50 C, D and H, commencing with the small dial, the letter C upon the circumference thereof is thrown to a position so that the line 50, identifying the letter C, comes into alignment with the indicating rib 48 upon 55 the outer face of the lid. When the dial is rotated the member 27 is also given a rotation therewith, by reason of the pin upon the member engaging a particular key slot corresponding to the letter C upon the circumference of the dial. This movement of the dial will bring the notch 33 in alignment with the tongue 35 which projects into the opening at the lower portion of the yoke. The dial 38 of next larger diameter 60 65 is then rotated to bring the indicating line

or groove 50, identified by letter D, into alignment with the indicating rib upon the outer face of the lid and which movement of the dial will cause the sleeve 26 carrying the same to rotate correspondingly, by reason 70 of the pin upon the sleeve engaging the key slot representing the letter D upon the dial 38. This movement of the sleeve will bring the notch 32 in alignment with the tongue upon the yoke. A similar rotary movement 75 is imparted to the dial upon the sleeve 25 and which will cause said sleeve to rotate to bring its notch also into alignment with the other two notches and with the tongue upon the yoke, which being done, the spring 80 upon the post will throw the yoke upward and release the key from the slot in the lower portion of the yoke, thus allowing the key of the switch to be turned for the purpose of turning on the current. 85

By the provision of a combination lock made in accordance with my invention, it will be noted that the combination may be easily and quickly changed by the manipulation of the dials to bring one or another 90 of the slots in position to receive the pin upon the sleeve. When the device is in a locked relation with reference to the key upon the switch, the lid will be securely held on by the means shown, making it 95 impossible to remove the lid until the disks are thrown into position to allow the yoke to automatically release the switch key.

What I claim to be new is:

1. A combination lock for switch keys 100 comprising in combination with the switch box, a casing fastened thereto, a yoke movable within the casing, concentrically mounted rotatable sleeves and a member with notched tumblers, a projection upon each sleeve and member, dials rotatably mounted upon said sleeves and member, and each having a plurality of key slots to engage said projections, a tongue upon the yoke adapted to engage the several notches 105 in said tumblers when in alignment to permit the movement of the yoke to release the switch key, a lid to the box, and means for holding the lid to the casing when the switch key is in locked relation. 110

2. A combination lock for switch keys comprising in combination with the switch box, a casing fastened thereto and provided with a recess in the wall thereof, a yoke within the casing and provided with a portion movable within said recess to hold the key in a locked or unlocked relation, combination mechanism for permitting the movement of the yoke in one direction, a lid to the casing, projections upon the inner face of the lid, and wings upon the yoke adapted to interlock with said projections to hold the lid upon the casing when the yoke is in a locked relation with reference to the switch key. 125 130 135

3. A combination lock for switch keys comprising in combination with the switch box, a casing fastened thereto and provided with a recess in the wall thereof, a yoke within the casing and provided with a portion movable within said recess to hold the key in a locked or unlocked relation, combination mechanism for permitting the movement of the yoke in one direction, a lid to the casing, projections upon the inner face of the lid, and wings upon the yoke adapted to interlock with said projections, a pin upon the yoke adapted to engage an apertured lug upon the lid when the yoke is in a locked relation with reference to the switch key.

4. A combination lock for switch keys comprising in combination with the switch box, a casing fastened thereto and provided with a recess in the wall thereof, a yoke within the casing and provided with a portion movable within said recess to hold the key in a locked or unlocked relation, combination mechanism for permitting the movement of the yoke in one direction, the wall of the casing having an opening therein, an integral hook shaped projection upon the yoke extending through said opening and adapted to engage over the marginal edge thereof, a lid for the casing and provided with projections upon the inner face thereof, wings upon the yoke for engagement with said projections, and a pin for moving the yoke, the inner face of the lid having an apertured lug to receive said pin.

5. A combination lock for switch keys comprising in combination with the switch box, a casing fastened thereto and provided with a recess in the wall thereof, a yoke

mounted within the casing and having a portion movable within said recess and slotted upon its lower end to receive the upper end of the switch key, a tongue projecting from said yoke, concentrically mounted rotatable sleeves and a member provided with notched tumblers, a pin projecting from each sleeve and member, dials mounted upon the sleeves and provided with radial key slots for engagement with said pins, a lid, lugs upon the inner face thereof, said yoke having oppositely disposed wings for engagement with said lugs when the yoke is in a locked relation with the switch key.

6. A combination lock for switch keys comprising in combination with the switch box, a casing fastened thereto and provided with a recess in the wall thereof, a yoke mounted within the casing and having a portion movable within said recess and slotted upon its lower end to receive the upper end of the switch key, a tongue projecting from said yoke, concentrically mounted rotatable sleeves and a member provided with notched tumblers, a pin projecting from each sleeve and member, dials mounted upon the sleeves and member and provided with radial key slots for engagement with said pins, a post fastened to one end of the yoke and extending through the wall of the casing, a spring upon said post adapted to throw the yoke to an unlocked position when the notches in the tumblers are in registration with said tongue.

In testimony whereof I hereunto affix my signature.

JOHN H. PILLINGS.
